R. SUCZEK

AUXILIARY APPARATUS FOR CONDENSERS

Filed April 18, 1922

INVENTOR.
Robert Suczek
BY
Cornelius L. O'nes
his ATTORNEY.

UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

AUXILIARY APPARATUS FOR CONDENSERS.

Application filed April 18, 1922. Serial No. 554,512.

To all whom it may concern:

Be it known that I, ROBERT SUCZEK, a citizen of the United States, residing in the city and county of Philadelphia, State of Pennsylvania, have invented certain new and useful Improvements in Auxiliary Apparatus for Condensers, of which the following is a specification.

My invention relates to apparatus for removing from a vessel, particularly one in which there is to be produced or maintained a vacuum, as a condenser or evaporator, elastic fluid, as air or gas, and liquid, as condensate or water, by separate ejectors which discharge the air or gas and condensate or liquid, respectively, through different or independent paths, to higher pressure or otherwise.

My invention resides in apparatus of the character hereinafter described and claimed.

For an illustration of one of the various forms my invention may take, reference may be had to the accompanying drawing, which is a vertical sectional view through a portion of the condenser and associated apparatus for removing air and condensate.

Referring to the drawing, C represents the shell of a condenser, for example, the shell of a surface condenser or a marine condenser such as used upon board ship to condense the exhaust steam from the engines or turbines. Both air and condensate are withdrawn through the outlet O. The condensate collects in the hot well or other receptacle H, the level of the water or condensate being indicated at W. In the condensate is submerged an ejector comprising the nozzle N aligned with the combining cone or guide tube B, which in turn is aligned with the diffuser or other tube D communicating with the suction chamber S, of any suitable type, of pump P¹, which is indicated as and preferably is a reciprocating wet air pump. Through the pipe A, controlled by the valve v, there is delivered under suitable pressure to the nozzle N any suitable motive fluid, as elastic motive fluid, as steam, or liquid, as water. The motive fluid delivered through the nozzle N causes the liquid or condensate to be drawn into the member B and to be delivered to the tube or diffuser D and discharged therefrom into the suction chamber S at higher pressure than obtains in the hot well H.

The air leaving the condenser C through the opening O passes upwardly to the ejector whose nozzle structure is indicated at M and having the diffuser or equivalent D¹. Motive fluid of any suitable character, preferably steam of suitable pressure, is delivered by the pipe E, controlled by the valve x, to the nozzle structure M, which delivers a jet of motive fluid which entrains the air, the mixture being delivered to the diffuser D at high velocity. The velocity of the mixture decreases and is converted into pressure in the diffuser D¹, and the mixture of steam and air is delivered either directly to the suction chamber S, or preferably, as indicated, to a condenser C¹, in which the motive fluid steam is more or less completely condensed, the condensate from the condenser C¹ and the air passing onward to the suction chamber S, from which the condensate from both condensers and the air from the condenser C is removed by the pump P¹.

The ejectors deliver, respectively, the air and condensate or other liquid against or to substantially the same pressure, to wit, that existing in the suction chamber S. The pressures of both the air and the liquid or condensate are increased by the ejectors to a substantially equal or common pressure, the air and condensate being then removed by the pump P¹ upon which the load is correspondingly less because of the preliminary compression of the air and increase in pressure of the liquid or condensate. The ejectors in effect assist the pump P¹ by preliminarily raising the pressure of the air and liquid or condensate.

While the ejectors herein disclosed are of simple single nozzle types, it will be understood that any suitable forms of ejector may be used, as for example, those employing a plurality of steam nozzles, or ejectors having annular nozzles and diffusers, or ejectors of the latter type in which the diffuser is disposed outside of and surrounds the annular nozzle which discharges radially into the diffuser.

The apparatus herein disclosed is disclosed in Letters Patent of the United States No. 1,342,471, granted me June 8, 1920.

What I claim is:

1. The combination with a receptacle for

liquid, of an ejector submerged in the liquid, a second receptacle to which said liquid is delivered by said ejector at higher pressure, and a second ejector delivering fluid at increased pressure to said second receptacle independently of said first named ejector.

2. The combination with a receptacle for liquid, of an ejector submerged in the liquid, a second receptacle to which said liquid is delivered by said ejector at higher pressure, and a second ejector delivering air at increased pressure to said second receptacle independently of said first named ejector.

3. The combination with a receptacle for liquid, of an ejector submerged in the liquid, a second receptacle to which said liquid is delivered by said ejector at higher pressure, a second ejector delivering air at increased pressure to said second receptacle independently of said first named ejector, and means for withdrawing the air and liquid from said second receptacle and raising them to higher pressure.

4. The combination with a receptacle, of a steam-operated ejector discharging air at higher pressure, a condenser into which the ejector discharge is delivered and in which the steam is condensed, the condensate and air delivered into said receptacle, and a second ejector delivering liquid from lower pressure into said receptacle.

5. The combination with a receptacle, of a steam-operated ejector discharging air at higher pressure, a condenser into which the ejector discharge is delivered and in which the steam is condensed, the condensate and air delivered into said receptacle, a second ejector delivering liquid from lower pressure into said receptacle, and means for withdrawing the air and liquid from said receptacle and raising them to higher pressure.

6. The combination with a condenser, of a receptacle for the condensate therefrom, an ejector submerged in said condensate, a second receptacle to which said condensate is delivered by said ejector, and a second ejector withdrawing air from said condenser and delivering it at higher pressure to said second receptacle independently of said first named ejector.

7. The combination with a condenser, of a receptacle for the condensate therefrom, an ejector submerged in said condensate, a second receptacle to which said condensate is delivered by said ejector, a second ejector withdrawing air from said condenser and delivering it at higher pressure to said second receptacle independently of said first named ejector, and means for withdrawing the air and liquid from said second receptacle and raising them to higher pressure.

8. The combination with a condenser, of ejectors for removing air and condensate therefrom through independent paths, a re-

ceptacle into which the discharges from said ejectors are delivered independently of each other at higher pressure, and means for removing the condensate and air from said receptacle to higher pressure.

9. The combination with a condenser, of an ejector for removing air therefrom, a second ejector submerged in the condensate and comprising a motive fluid nozzle, guide tube and discharge conduit, for ejecting the condensate while isolated from said ejected air in a path independent of the path in which the air is ejected from said condenser.

10. The combination with a vessel, of an ejector for withdrawing elastic fluid therefrom to produce a vacuum therein, and a second ejector for withdrawing liquid from said vessel submerged in said liquid and delivering it to higher pressure through a path independent of the discharge path of said first ejector, the suction pressures of said ejectors being substantially equal.

11. The combination with a vessel, of a steam-operated ejector for withdrawing elastic fluid therefrom to produce a vacuum therein, and a second ejector whose motive fluid is liquid for withdrawing liquid from said vessel submerged in said liquid and delivering it to higher pressure through a path independent of the discharge path of said first ejector, the suction pressures of said ejectors being substantially equal.

12. The combination with a marine condenser having a condensate outlet adjacent its bottom, of a condensate removing pump in communication with said outlet, and an ejector submerged in the condensate in advance of said pump for delivering said condensate to said pump and operated by motive fluid other than said condensate.

13. The combination with a marine condenser having adjacent its bottom an outlet for air and condensate, a pump for removing air and condensate in communication with said outlet through passages conducting air and condensate, respectively, an ejector in the air passage for withdrawing air from said condenser and delivering it to said pump, and an ejector submerged in the condensate in advance of said pump for delivering condensate to said pump.

14. The combination with a receptacle for liquid, of an ejector submerged in the liquid, a second receptacle to which said liquid is delivered by said ejector at higher pressure, and a second ejector compressing elastic fluid from subatmospheric pressure into said second receptacle independently of said first named ejector.

15. The combination with a receptacle for liquid, of an ejector submerged in the liquid, a second receptacle to which said liquid is delivered by said ejector at higher pressure, a second ejector compressing elastic fluid from subatmospheric pressure into said

receptacle independently of said first named ejector, and means for withdrawing said liquid and elastic fluid from said second receptacle and raising them to higher pressure.

16. The combination with a receptacle for liquid, of an ejector submerged in the liquid, a second receptacle to which said liquid is delivered by said ejector at higher pressure, and a second ejector compressing gas from subatmospheric pressure and delivering it into said second receptacle independently of said first named ejector, and means for withdrawing from said second receptacle said gas and liquid in mixture with each other and raising them to higher pressure.

17. The combination with a condenser, of a receptacle for the condensate therefrom, an ejector submerged in said condensate, a second receptacle to which said condensate is delivered by said ejector, a second condenser whose discharge delivers to said sec-

ond receptacle independently of said ejector, and a second ejector withdrawing air from said condenser and delivering it at higher pressure to said second condenser.

18. The combination with a condenser, of an ejector operated by elastic fluid submerged in the condensate of said condenser for removing it to higher pressure, a second ejector removing air from said condenser, and means for delivering the combined discharges from said ejectors to a higher pressure.

19. The combination with a condenser, of ejectors for removing air and condensate therefrom through independent paths, and means common to said ejectors for removing their combined discharges to a region of higher pressure.

In testimony whereof I have hereunto affixed my signature this 17th day of April, 1922.

ROBERT SUCZEK.
